UNITED STATES PATENT OFFICE.

HENRY M. CRIPPEN, OF ATHENS, OHIO, ASSIGNOR TO HENRY M. CRIPPEN, WILLIAM N. ALDERMAN, FIELD SCOTT, AND HARLEY H. HANING, ALL OF ATHENS, OHIO.

VERTICAL LOOSE-LEAF-BINDING MACHINE.

1,424,753.

Specification of Letters Patent. Patented Aug. 8, 1922.

Application filed June 9, 1921. Serial No. 476,272.

To all whom it may concern:

Be it known that I, HENRY M. CRIPPEN, a citizen of the United States, residing at Athens, in the county of Athens and State 5 of Ohio, have invented certain new and useful Improvements in Vertical Loose-Leaf-Binding Machines, of which the following is a specification.

My invention relates to improvements in 10 the loose leaf binding machines shown in my Patents 1,255,112, January 29, 1918, and 1,346,179, July 18, 1920.

The objects of the invention are to provide a vertically operating punching mechanism in a plane parallel to the receiving pins in order to lessen the length of throw of the punching head in its movement of transferring the punched sheets to the receiving pins; to actuate the punching 15 mechanism indirectly through gearing instead of directly by a lever whereby the length of throw of the punching head is lessened or shortened as before referred to; to provide an improved base and locking 20 means for the receiving pins; to provide improved clamp and sheet-carrier operating mechanism; to provide improved stripper mechanism for the punches; to provide an improved form of locking means for the 25 clamp bar against which the pile of sheets is compressed; to simplify and strengthen the main frame or casting carrying the anvil housing, fixed axle and mechanism mounted thereon; provide improved sheet- 30 guiding or gaging devices and to generally simplify and improve the constructions of the patents referred to, while still retaining the basic features thereof.

These objects I accomplish by the construction shown in the accompanying drawings, in which:

Fig. 1 is a side elevation partly in section of my improved machine.

Fig. 2 is a plan view thereof with the 45 sheet carrier partly broken away.

Fig. 3 is a vertical longitudinal section thereof with the parts ready to begin the punching of the sheets; the gages being omitted.

Fig. 4 is an elevation partly in section looking at the right hand end of the machine.

Fig. 5 is a vertical longitudinal section with the sheet carrier compressing a pile 55 of sheets.

Fig. 6 is a sectional elevation of the right

hand end of the machine, showing the carrier swung up with a punched and compressed pile of sheets.

Fig. 7 is a detail perspective partly in 60 section of the main square axle with the filing pins thereon.

Fig. 8 is a detail elevation to better show the compact relation of the actuating gear, operating hooks or cams, the ratchet and 65 adjacent parts.

Fig. 9 is a perspective of the sheet clamp.

Fig. 10 is a section on line 10—10 of Fig. 11.

Fig. 11 is a bottom plan view of the inner 70 end of the sheet carrier and adjacent parts.

Fig. 12 is a fragmentary vertical section, showing the sheet carrier moved to the right by lever 95.

An open rectangular base 1 is provided 75 which may be cast or formed of sheet metal, as may be desired. The longitudinal sides of the base 1 are provided adjacent to one end with uprights 2, 2 connected at their upper inner sides to the top crossbar 3 of a 80 vertically disposed main frame or casting 4, the side arms of which extend downward to the lower edges of the sides of the base 1, where they are apertured for the passage of the main operating rock shaft 10, the 85 ends of which are mounted in bearings 11 on the outer sides of the base; one end of the shaft extending beyond the side of the base where it is provided with any desirable operating means, a vertically disposed lever 90 12 being shown for this purpose. This rock shaft 10 is provided within the base 1 with two mutilated gears 13, 13, one at each end. Upon the inner side of the crossbar 3 is formed the tubular anvil casing 14 for 95 the tubular adjustable anvil 15 provided as in my said patents with series of punch apertures 16 with the middle set of which a transverse slot 17 in the anvil casing 14 registers. By passing a pin (not shown) 100 through this slot 17 into one of the apertures 16 the anvil 15 may be turned to bring any series of apertures in line with the punches to be presently described. The apertures 16, when so adjusted for operation, 105 face upwardly and the upper surface of the anvil casing forms a horizontal transverse ledge or support for the ends of the sheets to be punched. The anvil 15 is open at its ends and these open ends are in line with 110 apertures 5, 5 in the uprights 2, 2, so as to permit the insertion and removal of the

drawer 6; this drawer being like the one shown in Fig. 13 of my Patent 1,346,179 so that no further description of it is necessary. The inner vertical face of the crossbar 3 is provided with a gage plate 19 having operating pins 20 extending through apertures in the crossbar and provided with upturned ends 21 engaged by inclined slots 23 formed in an operating slide 22, held in its adjusted position by an angle clamp 24, mounted on a clamping screw 25 threaded into the outer face of crossbar 3. By adjusting the gage plate 19 towards and from the anvil apertures 16 the ends of the sheets 15 will engage the same and the point where they will be punched will be set or determined.

Near the lower ends of the side bars of frame 4 and on the inner edges thereof are formed projections 7, 7, which are transversely apertured for the passage of two journal pins 30, the inner ends of which extend into a transverse fixed axle 31 which lies parallel to the anvil 15. These journal pins 30 are secured to the axle 31 by two vertical pins 32 which project above the axle so as to enter apertures 34 in the base 35 of the filing pins 36. The lower side of this base 35 is flat to engage the flat upper side of the axle 31. This lower side of the base 35 is provided with a cushion 37 of some soft material, such as felt, so as not to mar the desk tops or the like. The inner edge of the base 35 is provided with recesses 38 and its ends are provided with rounded projections 38' for purposes to be presently described. The axle 31 is provided on its inner vertical face with recesses 31' with which the recesses 38 register. The journals are further locked rigidly by means of the set-screws 39 threaded into the side bars of frame 4.

Turning upon the journals 30 are two mutilated gears 40, 40 meshing with the larger operating gears 13, 13 on rock shaft 10. Rigidly connected to the gears 13, 13 to rock therewith are the two stripper-operating hooks or cams 41, 41, and the two sheet-carrier lifting cams 42, 42; spaces being left 50 between the stripper hooks or cams 41 and the gears 40, 40 for the lower ends of the punch actuating links 43, 43, which lower ends are pivoted eccentrically by pivots 43', see Fig. 8, to the gears 40, 40, while their 55 upper ends are pivotally connected to the ends of the punch-carrying crosshead 50 which is guided on guide bars 51, the lower ends of which are mounted to rock on the aforesaid journals 30 between the cams 42, 42 60 and the sides of the frame 4. At the inner sides of the frame 4 next to the ends of square axle 31 and upon the journals 30 are mounted locking hooks 80, 80 to engage the rounded projecting ends 38' of the pin base 35.

The crosshead 50, like those in my said patents, is provided with punches 52 registering with the anvil apertures, but these parts are now placed vertically and parallel to the filing pins so that the slotted sheet 70 guides of said patents are dispensed with and the path traveled by the crosshead and punches from the punching position to that of transferring of the sheets from the punches to the filing pins is only very short, 75 as will be readily seen. This vertical arrangement greatly simplifies and improves my prior constructions. The stripper 53 extends across the lower face of the crosshead 50 and the punches pass through open slots 80 53' in it. The stripper has depending arms 54 at its ends and these arms have guide lugs 55 on their inner sides sliding on the guide bars 51.

The outer sides of the arms 54 are provided at their lower ends with anti-friction wheels 56 engaged by the two hooks or cams 41, 41 for first moving the cross head, punches and stripper over the filing pins and then by moving the lever 12 to the left hand 90 dotted position in Fig. 1 depressing the stripper 53 when the punches 52 register with the filing pins 36 and so transfer the punched sheets from the punches to the pins.

The lower ends of the stripper arms 54 95 overlie the inner ends of two pivoted levers 57 pivoted at their outer ends to the base 1, and pressed upwardly a limited distance towards the arms 54 by springs 57'.

As the crosshead and stripper move downwardly in the act of punching, the inner ends of the spring-pressed levers 57 lie under the lower ends of arms 54 and so cause the stripper 53 to be held positively against the lower face of the crosshead 50, but when the crosshead and stripper are moved over the filing pins by throwing lever 12 to the left as in dotted lines, Fig. 1, in doing which the initial movement of hooks 41 to the right will move the cross head and stripper over 110 the filing pins and then the arms 55 will move from over the free ends of the levers 57 and so permit the hooks or cams 41, 41 to easily depress the stripper and force the apertured leaves down upon the filing pins. 115 Stops 8, 8 and 8', 8' limit the swing of the crosshead over the anvil.

In the return movement of the crosshead and stripper to the position over the anvil the arms 54 will be raised by springs 58 and again overlie the levers 57, and these springs 58 will also exert a rearward as well as an upward pull on the arms 55 and so draw the crosshead and stripper back over the anvil.

Springs 58 may be of any desired kind, but I have shown coiled springs coiled about pin 59 on the inner sides of the uprights 2, 2 with their free ends or arms extending under studs 61, projecting from the arms 55 120

just above the parts 56 engaged by hooks 41, 41. By means of the slots 53' in the stripper bar 53 the crosshead 50 and stripper 53 will be permitted to swing away from the upper 5 ends of the filing pins after the leaves have been stripped from the punches and without the stripper having to be raised above the upper ends of the filing pins. The time for movement is thus shortened.

10 As before stated, a gage plate 19 is provided for the end edges of the leaves to be punched and a gage carried by the crosshead 50 is provided for the side edges of the leaves. This side gage is formed of a spring 15 70 secured at one end to a pin 71 projecting from a slotted slide or plate 72 and having a depending arm 73 to engage the sheets. The spring 70 passes under a pin 74 and over a pin 75 which prevent it from turning 20 on pin 71 and yet allow it to flex upward should the lower end of arm 73 engage the top of a pile of sheets or top of anvil. The plate or slide 72 is secured in any desired position by means of a screw 76 passing 25 through its slot into the crosshead.

To operate the hooks 80 before referred to which engage the ends of the pin base 35 I provide a transverse rock shaft 81 mounted in bearings in the sides of the base and having 30 a crank handle 82 at the same side as the operating lever 12. This rock shaft 81 is provided between its ends with an eccentric 83 encircled by an eccentric strap 84 to which is connected one end of a rod 85, the 35 other end of which is connected to an arm 86 depending from the middle of a crossbar 87 rigidly connecting the two hooks 80 below their axes so that the turning of the rock shaft 81 will cause the forward or rear- 40 ward throw of the locking hooks 80.

At the right of the punching mechanism is located the horizontally disposed sheet-carrier 90 for the pile of punched sheets.

This sheet-carrier 90 overlies at its inner 45 end the base 35 which carries the sheet-receiving pins 36 and has slots 91 to straddle the pins 36. The outer end of the carrier 90 is pivotally mounted by means of pivots 92, 92 between the upper or outer ends of two 50 short arms 93, 93 rigidly connected by a transverse bar 94, one of these arms 92 being extended upwardly to form an operating handle 95.

The lower or inner ends of these arms 93, 55 93 are connected to the upper ends of vertical slides 96 by means of pivots 97; these arms 93, 93 projecting above and below the bar 94 and in effect forming T-ends therefor. The slides 96 are mounted in vertical guide- 60 ways 98 on the inner sides of the base 1 and their downward movement is limited by means of depending brackets 99 having in-turned flanges 100 at their lower ends, which flanges underlie the lower ends of the guide- 65 ways 98. The inner sides of these slides 96

are provided with actuating studs or lugs 101 adapted to be engaged by the operating arms 102 of vertically rocking and laterally sliding bell-crank levers 103 loosely mounted on the ends of rock shaft 81 and 70 provided with inwardly projecting sleeves 104 having their inner ends formed or provided with inclines or cams 105 acted upon by studs 106 projecting from rock shaft 81 to force the bell-crank levers 75 103 outwardly and under the studs 101 of slides 96 when the crank handle 82 is turned to the right, which movement of the crank handle also causes the locking hooks 80 to engage the ends 38' of base 35 carrying 80 pins 36.

The bell-crank levers 103 are drawn inwardly and from under the studs 101 by means of a contractile spring 108 whenever the crank handle 82 is swung to the left to 85 release the locking hooks 80.

The bell-crank levers 103 are actuated to raise and lower the right hand end of the sheet-carrier by means of operating rods 110 pivotally connected at their outer ends 90 thereto and pivotally connected at their inner ends to ratchet segments 111 secured to or forming parts of the gears 40, 40. These ratchets 111 are engaged by the inner ends (left) of pawls 112 pivoted between their 95 ends to the inner sides of base 1 and extending at their opposite ends under the rock shaft 81, which is there provided with projections or cams 113 adapted to depress the tails of the pawls against the action of 100 springs 112' and release their inner ends from the ratchets 111 when the crank handle 82 is swung to the left-hand position. The sheet-carrier 90 is prevented from swinging 105 too far down into the base by means of stop lugs 115 secured to the upper edges of the sides of the base. The sheet-carrier 90 is provided on its under side with a longitudinal shaft 119 having an operating handle 120 at its outer end projecting up through a 110 transverse slot 121 in the end of the carrier 90. A spring-pressed latch 122 has a projection 123 which locks the handle 120 when 115 swung towards the far side of the machine or away from the operator. The inner end 115 of the shaft 119 has a head 124 lying between the inner ends of two slides 125 mounted in guides 126 just in rear of the slots 91 and pressed towards each other by a bow spring 127 as in said prior patents. 120

These slides 125 are now, however, provided with two locking pins 128 adapted to pass under the square axle 31; the recesses 31' and 38 heretofore described being provided in the axle 31 and base 35 respectively 125 to permit the pins 128 to pass down below the axle and then be moved thereunder to lock the inner end of the carrier 90 down upon the base 35 during the sheet compressing operation. The outer ends of the slides 130

125 when the pins 128 are under the axle 31 project outwardly far enough to lie over the two lifting cams 42, 42 so that as the cams are raised the inner end of the carrier 90 5 will be correspondingly raised, at which time the lifting arms 102 of the bell crank levers 103 will be simultaneously raised to lift the outer end of the carrier. The carrier will be lifted evenly at both ends and so will 10 always lie horizontally. The two slides 125 are provided with friction grips or catches 130 formed of bent springs; one end of each of which is fixedly connected to its slide, while the outer or biting end lies next to an 15 aperture 131 in the carrier 90 just as in my Patent 1,346,179.

The clamp 135 has the depending legs 136 adapted to enter the apertures 131 and to be engaged by the grips or catches 130 20 as in my said patent, but it is held against the upward pressure of the rising carrier 90 during the act of compressing a pile of sheets by means of oppositely sliding bolts 137 mounted on its top crossbar and pivotally connected at their inner ends to a pivoted operating handle 138. By moving this 25 handle in one direction the bolts may be projected, at their outer ends, through apertures 139 in the uprights 2, 2, and so lock 30 the clamp.

The operation is as follows: The carrier 90 will be in its lowered position and its hand lever 95 will be swung up, which movement will move the carrier longitudinally and bring its slotted end over the base 35 of the receiving pins and the two locking pins 128 will at the same time pass under the fixed axle 31, thus securely locking the carrier down on the pin base and to the said axle. The crank handle 82 will also be 40 swung over to the left, which will throw the bell-crank levers from under the studs 101 so that the outer end of the carrier will be disconnected from its operating mechanism and will release the pawls 112 from 45 the ratchets 111 to allow the lever 12 to be moved in either direction. The handle 120 will be drawn towards the operator so that the slides 125 will be out of the paths of 50 their lifting cams and the hooks 80 will be moved from over the ends of the filing pin base. The lever 12 will now be moved to its middle position, which will bring the 55 punches into vertical alignment with the anvil apertures.

Sheets will now be placed with their ends to be punched overlying the anvil and evened by the gages.

The lever 12 will now be moved to the 60 right, which will cause the punch-operating links 43, 43 to pull the crosshead, its punches and the stripper downwardly until the punches pass through the sheets. By now moving the lever to its middle position the 65 cross head punches and stripper will be

lifted; the punched sheets being lifted with the punches. By now moving the lever 12 to the left the crosshead will be moved to the right until the punches register with the sheet-receiving pins 32 and then by continuing to move lever 12 to the left the stripper-operating hooks 41, 41 will depress the stripper and cause it to transfer the punched sheets to the pins 32. During these operations the sheet carrier 90 will not have 70 been raised or lowered at all, as in my patented constructions before referred to. 75

As soon as a pile of sheets has been formed ready for binding the clamp 135 will be placed thereover with its legs extending 80 down through apertures 131 and its locking bolts 137 entered into apertures 139.

Handle 120 is now moved away from the operator till locked by its spring catch and this will have moved the slides 125 outwardly and across their lifting cams. The crank handle 82 is now turned to the right, which will move the bell-crank levers 103 outwardly and bring their lifting arms 102 under the studs or lugs 101 and at the same 90 time throw the hooks 80 over the base of the receiving pins to lock the base independently of the carrier 90 and will also release the pawls 112 and allow them to engage the ratchet segments 111. Lever 12 will now be 95 moved to the right, which will cause the carrier to be lifted bodily at both ends simultaneously and then held up by the action of the ratchets 112.

This upward movement of the carrier 90 100 will force the pile of sheets upwardly against the clamp 135 and when the pile is sufficiently compressed handle 120 will be given a further movement away from the operator, which will cause a further outward movement of slides 125 and bring the friction catches 130 into biting engagement with the legs of the clamp. 105

The pile of punched sheets will now be firmly clamped to the carrier 90. If the 110 pile of sheets is to be secured together by binding sleeves such as shown at Y in my Patent 1,346,179 such sleeves will have been placed on the receiving or filing pins and their upper ends will now be upset, or where the leaves are to be sewed the carrier 90 with the pile of leaves will be swung up as in Fig. 10 of my Patent 1,255,112. This is accomplished by throwing lever 95 to the right until the parts assume the position 115 shown in Fig. 6.

The carrier or table 90 may be moved from over the filing pin base by simply swinging the hand lever 95 to the right, which will pull the inner end of carrier or table 90 125 from over the unlocked base of the filing pins and so permit the same to be lifted off of the fixed axle at any time.

Covers may be applied as in said patents when desired. 130

What I claim is:

1. In a loose leaf binding machine, the combination with a horizontally disposed anvil, a vertically reciprocating series of 5 punches co-operating with said anvil mounted to swing bodily laterally, and a stripper for the punches, of a vertically disposed series of receiving pins to one side of said anvil, and operating mechanism to reciprocate the punches, move them over the filing pins and then actuate the stripper towards the filing pins.
2. In a loose leaf binding machine, the combination with a horizontally disposed 15 anvil having punch apertures in its upper side, a vertically reciprocating series of punches registering with said apertures, of a vertically disposed series of receiving pins to one side of said anvil, and means for reciprocating the punches to punch the sheets and then moving the punches laterally over and into register with the upper ends of said pins to permit the transfer of the sheets from the punches to the pins.
3. In a loose leaf binding machine, the combination with a transverse anvil having apertures in its upper side, and vertically disposed punches registering with the anvil apertures, of vertically disposed receiving 25 pins to one side of the anvil and punches, and means for operating the punches and for automatically transferring the punched sheets to and transferring them downwardly upon said receiving pins.
4. In a loose leaf binding machine, the combination with an anvil, a series of punches co-operating therewith, a stripper for the punches, and a series of sheet-receiving pins to one side of the anvil and punches, of a main shaft provided with drive gears, driven gears meshing with the drive gears, and operative connections between the driven 30 gears and the punches and their stripper for first reciprocating the punches, then swinging them over the receiving pins and then actuating the stripper to force the punched sheets from the punches to the receiving pins.
5. In a loose leaf binding machine, the combination with a main shaft having gears, 40 a horizontal fixed axle above said main shaft and having journals at its ends and driven gears on said journals meshing with the first named gears, of a transverse anvil above the fixed axle and having punch openings in its upper side, a crosshead over the anvil and having punches to register with the anvil openings, swinging guide bars mounted at their lower ends on said journals and on the upper ends of which the crosshead slides, operating links pivoted at their upper ends to the ends of the crosshead and eccentrically pivoted at their lower ends to said gears, a stripper for the punches provided with depending side arms having lateral projections, hooks on the driven gears for actuating 45 the stripper, a spring exerting an upward and rearward pull on the stripper, and receiving pins to one side of the anvil and upon which the punched sheets are transferred from the punches by said stripper. 70
6. In a loose leaf binding machine, the combination with the transverse anvil having apertures in its upper side, and a gage in rear of and adjustable towards and from said apertures, of a swinging and sliding 75 punch-carrying crosshead having vertically disposed punches to enter said apertures and provided with a gage for the sides of the sheets to be punched, a series of receiving pins below and to one side of the anvil, and 80 mechanism for reciprocating the crosshead in the punching operation and then swinging it over the pins to permit transfer of the punched sheets from the punches to the pins.
7. In a loose leaf binding machine, the 85 combination with the punching and stripper mechanism, of a transverse fixed axle bar therebelow and having a flat upper side provided with upwardly extending base-engaging pins, and a series of sheet-receiving pins 90 having a base flat on its under side and apertured to receive the said base-engaging pins; the flat under side of the base having a cushioning material affixed thereto.
8. In a loose leaf binding machine, the 95 combination with a main shaft having gears at its ends, a fixed squared axle thereabove having round ends or journals, driven gears mounted on said journals and meshing with the first named gears, a reciprocating and 100 swinging punching mechanism above the squared axle and actuated from said driven gears, and a set of filing pins having a base removably secured to the upper side of the square axle with their upper ends extending 105 adjacent to one side of the punching mechanism to receive the punched sheets therefrom.
9. In a loose leaf binding machine, the combination with the punching and transfer 110 mechanism and receiving pins, of a sheet carrier extending at its inner end alongside the lower ends of the pins, mechanism for elevating both ends of the carrier simultaneously, and means for throwing out of 115 action the said elevating mechanism for both of said ends during the punching and transferring operation, whereby the carrier will remain stationary.
10. In a loose leaf binding machine, the 120 combination with the punching and transferring mechanism, including a transverse fixed axle bar therebelow and a set of receiving pins having a base removably seated on the upper side of said fixed axle bar, of a 125 sheet carrier or table movable longitudinally to overlie the base of said pins and also having locking means to underlie the said fixed axle; means for bodily lifting the said carrier or table, and means for withdrawing 130

the inner end of the table and said locking means from engagement with the pin base and fixed axle bar respectively.

11. In a loose leaf binding machine, the combination with a crosshead provided with punches, swinging guide rods on which the crosshead slides, operating means for said crosshead, links connecting the crosshead with its operating means and an anvil to co-operate with said punches, of a plurality of receiving pins over which the crosshead may be swung to bring the punches into alignment therewith, a vertically movable stripper mounted under the crosshead to transfer the sheets to said pins and having depending side arms, a spring exerting an upward and rearward pull on the stripper, spring-actuated arms underlying the lower ends of the stripper arms in their downward movement and from over which the lower ends of the stripper arms slip when the stripper swings over the receiving pins, and means for depressing the stripper when it so overlies the receiving pins.

12. In a loose leaf binding machine, the combination with the reciprocating and swinging crosshead provided with punches and an operating means for the crosshead and its punches, an anvil and sheet-receiving pins co-operating therewith, of a stripper on the under side of the crosshead and provided with transverse slots through which the punches project, means for depressing the stripper to transfer the punched sheets from the punches to said receiving pins, and springs exerting an upward and rearward pull on the stripper.

13. In a loose leaf binding machine, the combination with a set of receiving pins having a base, a cross axle bar on which said base rests removably, pivoted hooks on the cross axle adapted to hook over the ends of said pin base, a rod or shaft connecting said hooks, a transverse rock shaft having an eccentric, a connecting rod extending from said eccentric to the hook-connecting rod, a sheet carrier and means having pivotal connection to the carrier for imparting to the same longitudinal sliding movement towards and from the pin base and also vertically swinging movement at said outer end.

14. In a loose leaf binding machine, the combination with a main base, a transverse fixed axle bar, a set of receiving pins having a base removably resting thereon, and sheet-punching and transferring mechanism co-operating therewith, of a sheet-carrier having a slotted inner end overlying the pin base, vertical slides on the machine base provided with actuating studs, short arms pivoted at their lower ends to said slides and pivoted at their upper ends to opposite sides of the outer portion of said sheet-carrier, a

cross-bar connecting said arms, an operating handle for rocking said bar to move the carrier both longitudinally and vertically, lifting cams for the inner end of the sheet-carrier, laterally movable slides on the inner end of said carrier to engage the lifting cams, bell-crank levers adapted to be moved laterally under the lifting studs of said vertical slides, connecting rods leading from the bell cranks, curved ratchets on the axes of the lifting cams to which the inner ends of said connecting rods are pivotally connected, pawls engaging said ratchets, and a transverse rock shaft having lugs to release the pawls and also having means to move the bell-crank levers laterally outward under the studs of said vertical slides.

15. In a loose leaf binding machine, the combination with a main base having uprights, a vertically disposed frame between said uprights, an anvil at the upper end of said frame, a transverse fixed axle therebelow provided with journals at its ends, driven gears on said journal and having curved ratchets and sheet-carrier lifting cams, a main rock shaft having gears meshing with said driven gears, sheet-receiving pins having a base resting removably on said axle, hooks pivoted on said journals to engage the ends of the pin base, and punching and stripper mechanism co-operating with the anvil and receiving pins and operatively connected with said driven gears, of a sheet-carrier overlying the pin base at its inner end, vertical slides on the main base, connected arms pivoted to said slides and outer end of the sheet-carrier, a lever for swinging said arms, a transverse rock shaft provided with an operating handle and also provided with an eccentric operatively connected to the hooks engaging the pin base, pawls adapted to engage said ratchets, lugs on said rock shaft for releasing the pawls, bell-crank levers having cam sleeves loosely mounted on the said rock shaft, lugs or studs on the rock shaft for moving the bell-crank levers laterally into operative engagement with said vertical slides, links connecting the bell-crank levers with said curved ratchets, and laterally movable slides on the inner end of the sheet-carrier to engage the said lifting cams.

16. In a loose leaf binding machine, the combination with a base having uprights, and a transverse axle bar, and a set of receiving pins having a base removably mounted on said axle, of a sheet-carrier mounted within the base for vertical and longitudinal movement therein and having apertures, means for raising and lowering and shifting longitudinally the said carrier, a clamp bar for a pile of sheets having depending legs adapted to extend down through said apertures, means for locking the legs to the sheet carrier, and locking

means on the clamp by which to operatively engage the said uprights and hold the clamp against upward movement and means to move the carrier upwardly to compress a pile of sheets.

17. In a loose leaf binding machine, the combination with a main base having uprights provided with bolt openings, a transverse axle bar, and a set of receiving pins having a base removably mounted on said axle, of a vertically and longitudinally movable sheet-carrier mounted within the base and having apertures, means for operating said carrier, a clamp bar having legs adapted to extend down through the said apertures, means for locking said legs to the sheet-carrier, oppositely extending bolts on the clamp bar, and a lever connected to the inner end of the bolts to move them outwardly into engagement with the bolt openings.

18. In a loose leaf binding machine, the combination with a support having a ver-

tically recessed side and a set of filing pins provided with a base removably engaging said support, of a vertically and longitudinally movable sheet-carrier projecting at its inner end over said pin base and provided with apertures, a removable clamp having legs adapted to extend down through said apertures, of transverse slides on the carrier provided with lateral pins adapted to pass down through the axle recess and then be projected under the fixed axle, a longitudinal rock shaft having a head at its inner end to force said slides apart and project their ends beyond the carrier, means to hold the clamp against vertical movement relative to the carrier, means to lock the clamp legs to the carrier when the pile of sheets is compressed, and lifting means to engage the projecting ends of the said slides.

In testimony whereof I affix my signature.

HENRY M. CRIPPEN.
